UNITED STATES PATENT OFFICE.

LYMAN STEWART, OF TITUSVILLE, PENNSYLVANIA.

DEEP-WELL PACKING.

SPECIFICATION forming part of Letters Patent No. 252,275, dated January 10, 1882.

Application filed November 1, 1881. (No model.)

To all whom it may concern:

Be it known that I, LYMAN STEWART, a citizen of the United States of America, residing at Titusville, in the county of Crawford and State of Pennsylvania, have invented certain new and useful Improvements in Deep-Well Packing; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a vertical section of my improved packer with the rubber elongated for lowering into or removing from a well. Fig. 2 is a vertical section, illustrating the form which is assumed by the rubber when being compressed by the weight of the upper section of tubing. Fig. 3 shows a modification. Fig. 4 is a section taken on line *x x*, Fig. 1.

In the drawings, A B is the anchor, the part A being, by preference, a section of tubing reaching to the bottom of the well and having the part B, which is usually of greater diameter, connected thereto by means of a reducer. When used for flowing, the part B should be perforated, as at *b*.

C is a flange or coupling screwed to the upper end of tube B, and is of a diameter nearly equal to that of the well.

D is a section of tubing sliding within the tube B, and provided at its lower end with a flange or collar, *d*, which engages with a corresponding shoulder formed upon the flange and coupling C, thus constituting a telescopic joint. The upper face of the flange and coupling C is recessed, so as to form a gland around the lower end of tube-section D to receive a packing material, which is compressed by a follower, *e*, which screws into the upper end of the gland.

E F is a rubber annulus, having a flange, H, seated in its upper end, said flange having an internal thread to receive the upper screw-threaded end of tube-section D, the lower end of the annulus resting upon the flange-coupling C when the rubber is being compressed. The annulus is provided with two or more external ribs or cut-offs, *e f*, of rubber, which have

square shoulders both above and below, and which are, by preference, formed integral with the body of the annulus before it is vulcanized, and may be made by wrapping a strip of rubber around the annulus. The inner face of the annulus is concave near its lower end, as at G, for a purpose which will soon be explained. It will be readily understood that after the anchor A B strikes the bottom of the well, and its further descent is thereby checked, the weight of the upper section of the tubing, which is continued by successive lengths to the top of the well, will compress the annulus endwise and expand it laterally against the wall of the well, and also against the tubing, if the weight be great enough, thus making it a substantially solid compact mass; and it will be further understood that the expansion of the annulus will first take place at the rib or shoulder *e*, as indicated in Fig. 2, because the rubber is thinnest at that point, and hence offers the least resistance to outward expansion. Should the weight of the tubing be sufficient to force the upper tube-section down far enough, the rib or shoulder *f* will also be expanded against the wall of the well; but this result will not be accomplished until the rubber below rib *f* has been rendered very dense and the downward movement of the tubing has nearly ceased.

I am aware that a concave rubber annulus is shown in patent to Fowler and Morgan, November 28, 1865. Hence I do not claim an internally concaved or recessed rubber, broadly; but my construction possesses marked advantages over that shown in the Fowler and Morgan patent, because their rubber, being the thinnest midway between the ends, will be forced against the wall of the well at or near that central point first, and will then, by reason of the adhesion of that central part of the rubber to the wall of the well, be compressed above that central point until the weight of the tubing causes that tightly compressed rubber to slide down the face of the rock, thus producing great friction and seriously interfering with pressing that part of the annulus below its center against the wall of the well with sufficient firmness, whereas in my packer that part which is very close to the lower end is first forced against the wall of the well, and is therefore not after:

ward forced downward to any appreciable distance, the result being that the annulus is compressed with a substantially uniform pressure throughout its whole length, and the ribs or cut-offs *e f*, receiving the force of the pressure against the wall of the well, are rendered very dense, and effectually resist the passage of water downward and of gas upward. It will be further seen that after the rib or cut-off *e* has been pressed against the wall of the well a slight downward movement of that part of the annulus which is encircled by said rib will cause the upper face of the rib in Figs. 1 and 2 to assume a slightly concave or cup-shaped form, and that the same result will be produced after the upper rib or shoulder, *f*, has been forced against the wall of the well, whereby a more effective packing is made than could be produced with an annulus which is cylindrical in form, as by thus cutting off the water the weight of the whole column of water in the well is brought to bear directly upon the packing, thereby supplementing the weight of the upper section of tubing in making the packing sufficiently dense where a very light or short string of tubing is used.

In Fig. 3 I have shown a modified form of packer, which is more especially adapted for packing against gas-pressure from below, the difference between this structure and that shown in Figs. 1 and 2 being a change in the location in the cut-offs.

It will be noticed that in Figs. 1 and 2 the upper edge of the cut-off *e* is about opposite the center of the cavity *G*, the object in such arrangement being to insure that the upper edge of the cut-off shall be pressed firmly against the wall of the well soon after the operation of the rubber commences, and that a further and final compression shall not withdraw this upper edge of the cut-off from the wall of the well.

By changing the position of the cut-off to that shown in Fig. 3 I insure that its lower edge shall be first firmly pressed against the wall of the well, and also that a subsequent and further compression shall not withdraw said lower edge from contact with the wall of

the well nor reduce the pressure with which it is forced into that position, thus insuring that it shall effectually resist the passage of gas in an upward direction, as will be readily understood without further explanation.

I am aware that the patent to Fowler and Morgan November 28, 1865, (and others granted since that date,) shows a rubber annulus made thinner near its center than at its ends, in order to facilitate its central part being forced against the wall of the well with less pressure than would be required if it were not thus concaved internally. Hence I do not claim such construction, broadly; but when this thinnest portion is located about midway between the ends of the annulus the friction of the central part of the annulus against the wall of the well interferes materially with the packing, because more or less of the force exerted by the downward pressure of the upper tube-section is expended in overcoming this friction, instead of forcing the rubber against the rock; but this objection is obviated by my construction from the fact that that part does not descend after it has been forced against the wall. For this reason the weight of the upper section of tubing is much more effective in pressing the rubber against the wall in my packer than it is in those heretofore made, this feature being especially valuable in wells in which only a comparatively light weight of tubing can be used.

What I claim is—

1. In a deep-well packing, the combination, with the anchor and the upper sliding tubing-section, of the rubber annulus, concaved, as at *G*, near its lower end, substantially as set forth.
2. In a deep-well packing, a rubber annulus having an external rib, *e*, and an internal recess, *G*, opposite thereto, substantially as set forth.

In testimony whereof I affix my signature in presence of two witnesses.

LYMAN STEWART.
